DESIGN FOR A CIGARETTE LIGHTER

Abraham Saffron, Pittsburgh, Pa., assignor of one-half to Harry Lazier, Pittsburgh, Pa.

Application May 15, 1946, Serial No. 129,725

Term of patent 7 years

(CL. D48—27)

To all whom it may concern:

Be it known that Abraham Saffron, a citizen of the United States and a resident of Pittsburgh, in the county of Allegheny and State of Pennsylvania, has invented a new, original, and ornamental Design for Cigarette Lighter, of which the following is a specification, reference being had to the accompanying drawing, forming part thereof.

I claim:

The ornamental design for a cigarette lighter, as shown.

ABRAHAM SAFFRON.
